DESIGN FOR A BEAM COMPASS

John S. Mahler, Glen Ridge, N. J.

Application June 18, 1945, Serial No. 120,192

Term of patent 14 years

(Cl. D52—1)

To all whom it may concern:

Be it known that I, John S. Mahler, a citizen of the United States, residing at Glen Ridge, in the county of Essex, State of New Jersey, have invented a new, original, and ornamental Design for a Beam Compass, of which the following is a specification, reference being had to the accompanying drawing, forming part thereof.

Figure 1 is a perspective view of the beam compass showing my new design;

Figs. 2 and 3 are sectional views taken on the line 2—2 and 3—3, respectively, in Fig. 1, looking in the direction of the arrows.

I claim:

The ornamental design for a beam compass, as shown.

JOHN S. MAHLER.
